STRINGED ELECTRIC MUSICAL INSTRUMENT

Leo Krebs, 4138 Lankershim Blvd.,
North Hollywood, Calif.

Filed Dec. 5, 1962, Ser. No. 72,722

Term of patent 14 years

(Cl. D56—1)

FIGURE 1 is a front elevational view of a stringed musical instrument, showing my new design;

FIGURE 2 is a side elevational view with the tuning screw mechanism being omitted for convenience of illustration;

FIGURE 3 is a rear elevational view thereof; and

FIGURE 4 is an end elevational view.

The characteristic feature of my design resides in the randomly spaced musical grace notes imbedded in the transparent body of the musical instrument.

I claim:

The ornamental design for a stringed musical instrument as shown and described.
